UNITED STATES PATENT OFFICE.

LEON SUSSMAN, OF BAYONNE, NEW JERSEY.

SCREW-CUTTING MACHINE.

No. 800,339.

Specification of Letters Patent.

Patented Sept. 26, 1905.

Application filed January 7, 1904. Serial No. 188,068.

To all whom it may concern:

Be it known that I, LEON SUSSMAN, a citizen of the United States, and a resident of Bayonne, in the county of Hudson, State of New Jersey, have invented certain new and useful Improvements in Screw-Cutting Machines, of which the following is a specification.

My invention relates to improvements in screw-cutting machines or lathes, and has for its object to provide a simple structure for cutting threads on rods, pipes, or like blanks and to provide means for either manually or automatically interrupting the operation of the two at the proper moment.

To this end my invention consists in certain features of construction, which will be pointed out in the appended claim.

Reference is to be had to the accompanying drawings, which illustrate two typical forms of my invention, and in which—

Figure 1 is a side elevation of my improved screw-cutting tool in its closed position. Fig. 2 is a corresponding end view of the same. Fig. 3 is a side elevation of a slightly-different form of my invention in an open position. Fig. 4 is a corresponding end view. Fig. 5 is a longitudinal section of the two in a closed position. Fig. 6 is a longitudinal section of the second form of my invention, and Fig. 7 is a cross-section on line 7-7 of Fig. 6.

E designates a shank or rod which forms a continuation and at the same time a support for the body A, which is open at its opposite end and also has longitudinal slots in which the shanks of the jaws C are adapted to move radially, said jaws being pivoted, as indicated at C', and being subjected to the influence of springs C², which tend to throw the jaws into the open position. (Shown in Fig. 3.) In order to hold the jaws in the closed position, I provide a collar B, mounted to slide on the body A lengthwise and adapted to engage the shanks of the jaws C by means of projections B', preferably in the nature of adjustable screws, which are adapted to engage recesses C⁴ of said shanks and to move in the slots of the body A, which receive said shanks. Thus the collar B is at the same time held against turning. It will be understood that the jaws C will close more or less when the collar is in its forward position, (shown in Figs. 1 and 5,) according to the adjustment of the projections or screws B'. In order to project the collar into its forward position, I prefer to provide a lever A', fulcrumed on the body A at A⁴ and provided with an arm A², adapted to engage

the collar B and to move the same forward. Preferably the body A is formed with a lug A³, (see Fig. 6,) on which the arm or lever A' is pivotally mounted. When it is desired to open the jaws, so as to arrest the cutting action, the operator may slide the collar B back by hand. Where an automatic stop is desired, the collar B may be provided with a rod B³, adjustably secured thereto, as by means of a set-screw B⁴ in a sleeve B², which receives said rod B³. It will be understood that the forward end of the rod B³ will be engaged by the flanged carrier or chuck to which the blank, such as a pipe or rod, is secured, and thus the collar B will be thrown back at the proper moment according to the length to which the rod B³ projects, so that the projection B' will enter the recesses C⁴ and the springs C² will then cause the jaws to open suddenly, so as to arrest the cutting action. When the jaws C are in the closed position, the surfaces of the shanks of said jaws which are engaged by the projection B' are parallel with the outer surface of the body A upon which the collar B slides. It will thus be seen that as long as the projections B' engage the said shanks of the jaws C, even while the collar B is being moved back, the said jaws will remain closed and will open only when the said projections B' enter the recesses C⁴. With this structure it is therefore possible to cut a thread of even depth clear to the end of the work, which cannot be done in devices where the jaws open gradually. By adjusting the screws B' so that they will project more or less from the collar B the position of the jaws relatively to each other when they are closed can be regulated so that the same tool can be used for threading blanks of different diameters. It will be understood that the jaws C receive dies on their forward ends, these dies being exchangeable, so that threads of different diameters and different pitch may be cut.

In Figs. 1 and 2 I have shown cutters D, which are secured to the jaws C by screws D'.

In Figs. 3 and 4 I have shown two semi-circular segments D², each of which has two cutters and is secured to the corresponding jaw C by screws D³.

In order to provide for cases in which a thread is to be cut on a rod or pipe at a distance from its end, I prefer to make the body A with an axial opening C⁵, into which the end of the rod or pipe may project. The time at which the tool begins to cut is gov-

erned by sliding the collar B forward through the medium of the lever A'. The time the cutting action ceases is governed by the adjustment of the rod or projection B³, which 5 extends lengthwise to the body A.

In the form of construction illustrated by Figs. 6 and 7 I have substituted the following device for the parts B² B³ B⁴: The collar B is provided with a pin F, extending diametrically through the body A and adapted to slide in slots A³ of said body. Where this pin crosses the central aperture or bore of the body, it is connected with a projection or rod G, extending lengthwise within the body. 10 It will be understood that this rod G is in the path of the blank on which the screw-thread is to be produced, and therefore at the proper moment the blank itself will engage said rod and shift the collar B back to a position in 15 which the jaws C are released. To provide for longitudinal adjustment of the rod G, a set-screw F' may be used, said screw fitting into the pin F.

I claim as my invention and desire to secure by Letters Patent—

25

The combination with the body having a guide-surface and die-holding jaws pivotally carried by said body, of a collar mounted to slide on said guide-surface and provided with projections adapted to engage the jaws, those surfaces of the said jaws which are engaged by the said projections being parallel in the closed position of the jaws, with the said guide-surface, the said jaws being provided near their pivots with recesses into which 30 said projections are adapted to enter at the time the jaws open, to cause the said jaws to open suddenly.

In testimony whereof I have hereunto set my hand in the presence of two subscribing 35 witnesses.

LEON SUSSMAN.
